UNITED STATES PATENT OFFICE.

FRANK BOBNER, OF RAYMOND, WASHINGTON.

BUTTON FASTENER.

Application filed November 14, 1923. Serial No. 674,656.

To all whom it may concern:

Be it known that FRANK BOBNER, a citizen of the United States, residing at Raymond, in the county of Pacific and State 5 of Washington, has invented certain new and useful Improvements in Button Fasteners, of which the following is a specification.

This invention relates to a button fastener 10 and has for its principal object to provide a simple and efficient device which will enable the button to be fastened to a garment without the necessity of having to employ thread for the fastening means.

Another important object of the invention 15 is to provide a button fastener of the above mentioned character which is of such a construction as to enable the button to be detachably secured upon a garment and is furthermore held in position upon the garment 20 without the possibility of the button becoming accidentally lost or otherwise disengaged from the garment.

A still further object of the invention is 25 to provide a button fastener of the above mentioned character, which is simple in construction, inexpensive, strong, durable and further well adapted for the purposes for which it is designated.

Other objects and advantages of this invention will become apparent during the course of the following description.

In the accompanying drawings forming a part of this specification and in which like 35 numerals designate like parts throughout the same:—

Figure 1 is a front elevation of a portion of a garment showing a button with my button fastener associated therewith.

Figure 2 is a rear elevation.

Figure 3 is a central vertical section taken on line 3—3 of Fig. 1, and

Figure 4 is a detail view of my button fastener showing the parts in disassembled 45 relation.

In the drawings wherein for the purpose of illustration is shown the preferred embodiment of my invention, the numeral 1 designates a portion of the garment to 50 which is attached the button 2 by means of the button fastener hereinafter to be more fully described. It being further understood that the button 2 is of the usual construction and it is not thought to go further 55 into detail as to the construction of the

button only as to state that the button 2 is provided with the apertures 3 for the purpose of receiving the fastening means.

My button fastener comprises the staples 4 and 5 respectively and are preferably 60 formed of non-corrodible wire, the metallic plate 6 which is provided with apertures 7 therein which are adapted to register with the apertures 3 provided in the button 2 and the felt disc 8. These elements are 65 more clearly shown in Fig. 4 of the drawings and their cooperation with each other will be more fully set forth in the following paragraphs.

In assembling the various parts of my 70 metallic fastener when it is desired to secure a button upon a garment, the button 2 is placed on one side of the garment 1 and these staples 4 and 5 are adapted to pass through the apertures 3 provided in the button 2 and the same will pierce the cloth and extend through the opposite side thereof. It being further understood that the staples 4 and 5 respectively are so adapted 75 to pass through the aperture 3 in the button 2 so as to extend diagonally across each other as more clearly shown in Fig. 1 of the drawings. Adapted to receive the arms 9 of the staples 4 and the arms 10 of the staple 5 is the metallic plate 6 and this is 80 accomplished through the medium of the aperture 7 provided in the plate 6 and which register with the apertures 3 provided in the button 2 it being further understood that the plate 6 is of the same 85 size as the button 2.

The felt disc 8 is then forced over the free end of the staples 4 and 5 until the same rests against the outer face of the metallic plates 6 and when in this position, 95 it will be seen that the free end of the arms 9 of the staple 4 are bent in opposite direction around the edges of the felt disc 8 and the metallic plate 6 and are then bent inwardly to rest upon the upper face of the 100 metallic plate 6, thereby being disposed between the garment 1 and the metallic plate 6. The other staple 5 has its free end of the arms 10 embedded in the felt disc 8.

As seen in Fig. 4 in the drawings the 105 staple 4 is longer than the staple 5 thereby enabling the arms of the staple 4 to have its free ends bent around in the desired manner as heretofore set forth whereas the arms 10 of the staple 5 has its free ends bent 110

inwardly and terminating and embedded in the felt disc 8 as more clearly shown in Figs. 2 and 3 of the drawings.

By bending the free ends of the arms 9 of the staple 4 inwardly between the garment 1 and the metallic plate 6 and also by embedding the free ends of the arms 10 of the staple 5 in the felt disc 8 the sharpened points of the staples are prevented from projecting outwardly whereby the same may be accidentally brought in contact with the other pieces of clothing or the hands of the person which would result in serious damage.

The simplicity with which this button may be fastened to a garment by means of the button fastening means above described enables a button to be securely held in proper position upon the garment and will also prevent the casual displacement of the button from the garment. Whenever it is desired to remove the button 2 from the garment it is only necessary to straighten the free ends of the staples 4 and 5 and remove the felt disc 8 and the metallic plate 6 from the arms of the staples and will thereby enable the button 2 to be readily detached from the garment. Furthermore the simplicity of the construction of my button fastener enables the same to be readily and easily attached to any button provided with apertures and will also be obtainable at a minimum cost.

From the foregoing description of the construction of my improved apparatus, it will be seen that I have provided a simple, inexpensive and efficient means for carrying out the objects of the above invention, and while I have particularly described the elements best adapted to perform the functions set forth, it is obvious that various changes in form, proportion and in the minor details of construction may be resorted to, without departing from the spirit or sacrificing any of the principles of the invention.

What I claim as new and desire to secure by Letters Patent is:—

1. A button fastener for buttons comprising a pair of staples, each having its arms adapted to pass through apertures provided in said button and the garment with which said button is associated, a metallic plate provided with apertures registering with the first mentioned apertures

and adapted to receive the arms of said staples, a felt disc fitting against the outer face of said metallic plate and adapted to receive the arms of said staples, the free ends of one of said staples being embedded in said felt disc, and the free ends of the other staple adapted to be bent in opposite directions around the edges of said felt disc and metallic plate and disposed inwardly between the upper face of the metallic plate and the garment.

2. A button fastener for buttons comprising a pair of staples, each having its arms adapted to pass through apertures in said button and the garment with which the button is associated, a metallic plate provided with apertures registering with the first mentioned apertures, a felt disc adapted to fit against the outer face of said metallic plate, the arms of said staples adapted to pass through the apertures in said metallic plate and through said felt disc, the free ends of one of said staples being bent in opposite directions around the edges of said felt disc and metallic plate and disposed inwardly on the upper face of said metallic plate, the free ends of the other staple being bent inwardly and embedded in said felt disc.

3. A button fastener for buttons comprising a pair of U-shaped staples of unequal lengths, each having their arms adapted to pass through pairs of apertures provided in said button, the crown portions of said staples crossing on the upper face of said button, a metallic disk plate provided with apertures registering with the apertures in said button and adapted for application to the opposite face of the garment to which the button is applied, a felt disk applied to the outer face of said metal disk plate receiving therethrough the arms of said staples, the free ends of the arms of the shorter staple being bent inwardly and embedded in the outer face of said felt disk and the free ends of the arms of the longer staple being bent in opposite directions outwardly around the edges of said felt disk and metallic disk plate and disposed inwardly on the upper face of said disk plate, as and for the purposes described.

In testimony whereof I affix my signature.

FRANK BOBNER.
